UNITED STATES PATENT OFFICE.

FRANK N. WILCOX, OF NEW ORLEANS, LOUISIANA.

OIL-BURNER.

SPECIFICATION forming part of Letters Patent No. 715,227, dated December 2, 1902.

Application filed March 18, 1902. Serial No. 98,815. (No model.)

To all whom it may concern:

Be it known that I, FRANK N. WILCOX, a citizen of the United States of America, residing at New Orleans, in the parish of Orleans and State of Louisiana, have invented 5 certain new and useful Improvements in Oil-Burners; and I do hereby declare the following to be a full, clear, and exact description of the invention, such as will enable others skilled in the art to which it appertains to make and use the same.

My invention relates to improvements in oil-burners; and it consists in providing a suitable oil-burner in which the oil is distributed by and consumed from the surface 15 of water.

The invention also consists of certain novel features which will be hereinafter described and claimed.

Reference is had to the accompanying drawings, in which the same parts are indicated by the same letters throughout the several views.

Figure 1 represents a plan view of a burner, 25 part of the cover being broken away. Fig. 2 represents a section along the broken line 2 2 of Fig. 1 and looking in the direction of the arrows. Fig. 3 is an inverted plan view of the annular perforated plate used in the 30 burner, and Fig. 4 represents a section along the line 4 4 of Fig. 1 and looking in the direction of the arrows.

A represents the shell or body of the burner, which is provided with a flange A', having a 35 vertical ring a'. Between the body of the burner and this vertical ring are a number of ribs A², radially disposed, which ribs are V-shaped, as shown in cross-section in Fig. 4, to form V-shaped troughs a², with interposed 40 air-passages a³. These V-shaped troughs a² open into the liquid-chamber in the bottom of the burner, as shown to the left of Fig. 2.

Through the center of the body A, I provide a hollow cylinder A⁰, projecting above the surface of the liquid, as shown in Fig. 2. This cylindrical opening allows a passage upward therethrough of air, and thus prevents excessive heating of the liquid contents of the burner and also supplies air to the burning- 45 surface of the oil.

B represents an annular scattering-plate which slips over this cylindrical center of the

burner-body and rests on a shoulder a. This annular plate is perforated, as at b, the said perforations being conical in the form of inverted funnels for the better scattering of the oil and water passing therethrough. 55

Oil is fed into the base of the burner through a pipe C from any suitable source of supply, and water is pumped into the base of the burner through the pipe D. If it be desired to wash out the burner, the valve d may be closed and the contents of the burner may be drawn off through the waste-pipe D'.

E represents a cap, perforated as at e, 65 which covers the center of the burner and serves to deflect outward the air passing up through the cylindrical aperture A⁰, at the same time to confine the combustion to the annular space outside of said cap and above, 70 the V-shaped troughs a². This cap may be omitted, if desired.

F represents a pipe to carry off the liquid contents of the burner above a certain level, which may be used when the oil and water 75 become too intimately mixed, it being preferable to have the oil mainly floating on the top of the water at the time it is being consumed. By drawing off the oil and water through the pipe F above the level of the orifice of said pipe fresh oil and water may be injected through the pipes C and D, and thus 80 the proper proportions and admixture may be secured.

The supply of oil and water may be regulated by valves controlling the pipes C and D or in any other convenient way. 85

The operation of the device is as follows: Oil and water are fed in through the pipes C and D and rising together, the oil principally 90 above the water, will pass through the opening d upward beneath the cap E. Thence spreading laterally the oil and water will flow into the V-shaped troughs a², and the oil being ignited by a small piece of waste soaked 95 in oil or in any other convenient way combustion is started. Air rises through the inlets a³ and supplies the necessary oxygen to convert the carbonic acid of the flame into carbon dioxide and to cause perfect combustion. The air coming up through the central 100 passage A⁰ serves to prevent the liquids in the burner from becoming too hot prior to combustion, thus preventing the evaporation

of an excessive amount of water. At the same time some of this air passes under the edges of the cap and over the oil in the V-shaped troughs, thus further aiding in the combustion.

While burning, the air evaporates more or less of the water, and the steam so formed in passing through the boiler or over the other object to be heated gives up a large part of its heat. The water thus not only serves as a medium for finely distributing the oil over a wide surface from which surface the oil is consumed, but it also serves to lessen the intense heat of the burning oil, which is objectionable in most of the uses to which such burners are applied.

By the herein-described apparatus complete combustion of the oil is secured, and a cheap, simple, and effectual apparatus is provided in which the desired result is economically obtained.

Having thus described my invention, what I claim, and desire to secure by Letters Patent of the United States, is—

25 1. An oil-burner comprising an annular chamber with air-passage through the center thereof, the said chamber having a narrow base and an enlarged upper portion provided with a series of radial troughs to receive 30 the liquid, with air-passages between said troughs, with means for simultaneously feeding oil and water into the base of said chamber, whereby the oil is caused to pass through and spread out over the surface of the water 35 in the enlarged portion of said chamber, substantially as described.

2. An oil-burner comprising an annular chamber with air-passage through the center thereof, the said chamber having a narrow 40 base and an enlarged upper portion, provided with a series of radial troughs to receive the liquid, with air-passages between said troughs, with means for simultaneously feeding oil and water into the base of said chamber, whereby the oil is caused to pass through and spread out over the surface of the water 45 in the enlarged portion of said chamber and a scattering-plate arranged in said chamber below the normal surface of the oil, substantially as described.

50 3. An oil-burner comprising an annular chamber with an air-flue through the center thereof, the said chamber having a narrow base and an enlarged upper portion provided 55 with a series of radial troughs to receive the liquid, with air-passages between said

troughs, a cap above said air-flue and extending over the inner ends of said troughs, and means for simultaneously feeding oil and water into the base of said chamber, whereby the oil is caused to pass through and spread out over the surface of the water in the enlarged portion of said chamber, substantially as described.

4. An oil-burner comprising an annular 65 chamber with an air-flue through the center thereof, the said chamber having a narrow base and an enlarged upper portion, provided with a series of radial troughs to receive the liquid, with air-passages between said 70 troughs, a cap above said air-flue and extending over the inner ends of said troughs, and means for simultaneously feeding oil and water into the base of said chamber, whereby the oil is caused to pass through and spread out 75 over the surface of the water in the enlarged portion of said chamber and a scattering-plate arranged in said chamber below the normal surface of the oil, substantially as described.

5. An oil-burner provided with a central 80 chamber, with radial troughs exterior to and connected to said central chamber, air-passages opening upward between said troughs, a cap above said chamber and extending over the inner ends of said troughs, and means for 85 supplying oil and water to the base of said chamber, substantially as described.

6. An oil-burner provided with a central annular chamber with a vertical air-passage therethrough, radial troughs exterior to and connected to said central chamber, air-passages opening upward between said troughs, a cap above said air-flue and extending over the inner ends of said troughs, and means for supplying oil and water to the base of said 95 chamber, substantially as described.

7. An oil-burner provided with a central annular chamber with a vertical air-passage therethrough, radial troughs exterior to and connected to said central chamber, air-passages opening upward between said troughs, a scattering-plate below said troughs, a cap above said air-flue and extending over the inner ends of said troughs, and means for supplying oil and water to the base of said chamber, substantially as described.

In testimony whereof I affix my signature in presence of two witnesses.

FRANK N. WILCOX.
